(54) **PACKING COTTON**

(76) Inventor: **James McClelland**

James H. Ab. Clelland & Resident two years &
upwards in the United States

Letters Patent

United States, December 28th 1826.

The schedule referred to in these Letters Patent, & making part of
the same, containing a description in the words of the said James, H.
Clelland himself of his improvement in the machine for picking
or packing cotton.

The principle of this invention consists, first, in the use of a lever
of the second order (the direction of its motion being perpendicular
to the horizone), second in a screw standing perpendicular to the power
end of the lever to which it is attached, & third of a lever wheel
wheel, with a screw & pinion for receiving & revolving the rammer
of the cotton into which it works.

The operation of this machine is first (after the cotton is put
into the racking box) by turning the lever wheel, which turns the
wheel, which presses down the rammer of the cotton to a certain
point, corresponding to the power applied; 2nd by bringing the
great lever (which during the first operation is slid on one
side) over the rammer, which serves it as a fulcrum & turning
the screw at the power end of the lever by means of hand spikes
which by means of a female screw block above, pressed down the
end of the lever which remains fixed at the other end, & thus
completes the operation of packing the cotton.

The lever not having a sufficient length of 6^{ft} for motion
of the fulcrum point to give depth of box for the cotton, is
made to slide to one side, making way for the rammer to pass
up high enough to admit the cotton which is done by the rack
& pinion method already mentioned.

The effective power produced by means of this arrangement
of lever & screw is equal to 50,000 pounds from the exertion of one
man, which enables two men with ease to pack 1000 wt of

otion in the common space allowed in the square bags.—The length of the lever from the fulcrum is in this case 16 feet 6 inches.
